STRAP APPLYING TOOL

Paul Farkas, Fair Lawn, N.J., assignor to Thomas & Betts Corporation, Elizabeth, N.J.

Filed July 7, 1970, Ser. No. 23,852

Term of patent 14 years

Int. Cl. D8—05

U.S. Cl. D8—68

FIG. 1

FIG. 2

FIG. 3

FIG. 4

FIG. 5

FIG. 6

FIG. 1 is a left side elevational view of a strap applying tool;

FIG. 2 is a front elevational view thereof;

FIG. 3 is a top plan view thereof;

FIG. 4 is a bottom plan view thereof;

FIG. 5 is a rear elevational view thereof; and

FIG. 6 is a right side elevational view thereof.

I claim:

The ornamental design for a strap applying tool, substantially as shown and described.
